UNITED STATES PATENT OFFICE.

JAMES E. LOCKWOOD, OF PEORIA, ILLINOIS.

DESIGN FOR A GAS AND VAPOR BURNER.

45,390.

Specification for Design.

Patented Mar. 10, 1914.

Application filed January 5, 1914. Serial No. 810,515. Term of patent 3½ years.

To all whom it may concern:

Be it known that I, JAMES E. LOCKWOOD, a citizen of the United States, residing at Peoria, in the county of Peoria and State of Illinois, have invented a new, original, and ornamental Design for Gas and Vapor Burners, of which the following is a specification, reference being had to the accompanying drawing, forming part thereof.

The figure is an elevation of a gas and vapor burner, showing my new design.

I claim:—

The ornamental design for a gas and vapor burner, as shown.

In testimony whereof I affix my signature, in presence of two witnesses.

JAMES E. LOCKWOOD.
